UNITED STATES PATENT OFFICE.

GILBERT H. BLAKESLEY, OF BRISTOL, CONNECTICUT.

GARTER.

SPECIFICATION forming part of Letters Patent No. 660,553, dated October 30, 1900.

Application filed June 21, 1898. Serial No. 684,077. (No model.)

To all whom it may concern:

Be it known that I, GILBERT H. BLAKESLEY, of Bristol, in the county of Hartford and State of Connecticut, have invented certain new and useful Improvements in Garters; and I do hereby declare the following to be a full, clear, and exact description of the invention, such as will enable others skilled in the art to which it appertains to make and use the same.

10 The present invention relates to garters, and more particularly to that type of garter adapted for men's wear. Such garters as heretofore constructed have usually embodied an elastic leg-band, which encircled the leg of the wearer between the knee and the calf, and a pendent clasp, which was so connected by means of cord or webbing with the leg-band that the strain of the clasp attached to the sock was transmitted to and depended on to draw the leg-band closely about the leg in order that said band should be held in place and perform the proper function. This was usually accomplished by providing a sliding connection between the part which 15 supports the clasp and the leg-band. The proper fit of the garter under these conditions was dependent upon the length of the leg portion of the sock, which if too long would not place sufficient strain upon the leg-band.

20 to retain it in position upon the leg and which if too short would place so much strain thereon as to cause the leg-band to unduly compress the leg and retard the proper circulation of the blood therein to the great dis- 25 comfort of the wearer.

The object of the present invention is to so construct a garter as to render the retaining of the leg-band in position on the leg entirely independent of the strain imparted thereto 30 by the supporting-clasp and to generally render the device more comfortable and effective in use.

To the above ends the present invention consists of the improved garter, which will be 35 hereinafter described and claimed.

The present invention is illustrated in the accompanying drawings, in which—

Figure 1 shows a perspective view of the complete garter. Fig. 2 shows an enlarged 40 detail illustrating the method of connecting the leg-band and the retaining and supporting sections. Fig. 3 illustrates the manner

of forming the elastic sections. Figs. 4, 5, 6, and 7 are details of construction.

Similar reference characters will be employed throughout the specification and drawings to designate corresponding parts.

In the drawings, A represents the leg-band, which is preferably formed of a band of inelastic webbing. To one end of the leg-band 55 is permanently connected the retaining-section C and the supporting-section C' C', which at their opposite ends are connected with a short tab T, which is detachably connected to the leg-band A by means such as a ball-and-socket fastening a, one member of which is carried by the leg-band A and the opposite member by the tab T. (See Figs. 1 and 2 of the drawings.)

The retaining and supporting sections C and 70 C' C' are formed of elastic material, such as elastic cords, consisting of rubber strands covered by a suitable loosely-braided textile fabric and which is well-known to those persons skilled in this art and need not be described. These elastic sections C and C' C' 75 may be connected to the band A and the tab T in any suitable manner, the only requisite being that they shall be entirely independent of each other, the retaining-section C acting 80 to retain the leg-band A in position upon the leg of the wearer and the supporting-section acting to support the sock. As shown in the drawings, they are connected as follows: At each end the sections C and C' C' are provided 85 with clips c, which, as shown in Fig. 7, have wings c², which are designed to be folded down around the ends of the elastic cords comprising the sections C and C' C' and confining both the textile braided covering and the rubber 90 strands. The manner of applying such clips to the elastic cords is shown in Fig. 3 and may be described as follows: A section of the cord of indefinite length is extended or placed under tension, and while thus held the pairs of 95 the clips c are secured to the cord in close proximity to each other at the proper intervals along the cord to produce elastic sections of the length required. After the clips have been placed upon the elastic cords such cords 100 are cut between the clips, as shown at c², thus producing the sections with the clips c at the ends, as shown clearly in the drawings. Each clip has a projecting tongue c', which is passed

105

through slots *d* of plates D and turned over or clenched, thus fastening the ends of the elastic retaining-section S and the elastic supporting-section to the plate D. The plates D 5 are provided with sleeves which engage connecting loops or links E, which are connected, respectively, to one end of the leg-band A and the tab T in any suitable manner, as by doubling the band and tab upon themselves 10 through the loops E and securing the doubled-over portions in a manner well known to those persons skilled in this art. The end of the leg-band is preferably connected to a buckle or slide *a'*, whereby said band may be adjusted 15 to the requirements of the individual wearing the garter and to regulate the tension of the elastic retaining-section C.

At the medial portion of the elastic supporting-section C' C' there is secured in the 20 usual pendent position the supporting-clasp D', which may be of any usual or preferred construction.

If desired, the metallic connections at the 25 ends of the sections C and C' C' may be covered, as by coverings of silk or other suitable material *e*, which is usually secured thereto by sewing.

It will be noted that in my improved garter the leg-band A is formed of inelastic material 30 and may be adjusted in length to regulate the tension of the elastic retaining-section C, so as to be comfortably retained in proper position on the leg of the wearer and that the constant binding effect on the muscles at the back 35 of the leg, which is present in those garters having elastic leg-bands, is done away with. It will be further noted that the strain incident to supporting the sock is transmitted to

the leg-band by an elastic supporting-section, which is entirely independent of the elastic 40 retaining-section, and no amount of strain applied to the supporting-section will tend to shorten or increase the tension of the retaining-section.

As shown in the drawings, I prefer to form 45 the elastic supporting-section of a smaller, and consequently more elastic, cord than the retaining-section and also somewhat longer than the retaining-section, so that the members C' C' of the supporting-section will normally assume an angular position with relation to each other.

Having described the construction and mode of operation of my invention, I claim as new and desire to protect by Letters Patent of 55 the United States—

1. A garter comprising an inelastic leg-band, an elastic retaining-section and an independent elastic supporting-section connecting the ends of the leg-band, and a supporting-clasp supported by the supporting-section, substantially as described.

2. A garter comprising an inelastic leg-band, an elastic retaining-section connecting the ends of said band, and an elastic supporting-section supported by the ends of said band, the retaining-section being of relatively less elasticity than the supporting-section, substantially as described.

In testimony whereof I have signed this 70 specification in the presence of two subscribing witnesses.

GILBERT H. BLAKESLEY.
